APPARATUS FOR FORMING CONCRETE
STRUCTURES

William R. Marsden, Brooklyn, N. Y.

Application September 6, 1932, Serial No. 631,812

3 Claims. (Cl. 61—57)

This invention relates to new and useful improvements in concrete piles and the like, and the method and means of constructing them.

Generally stated, there are at present two forms of cast in place concrete piles in use, namely, the cased and the uncased. In the driven cased type, a mandrel surrounded by a light steel shell is driven into the ground. When the required depth is reached the mandrel is removed, concrete is poured into the shell, and the shell is left permanently in the ground. In the uncased type of pile, after the concrete is poured into the driving shell, and before it is permitted to set, the steel shell is removed.

It is the object of my invention so to construct a concrete pile that the objection to such pile structures as to cost and quality are eliminated and that full protection be afforded to the pile in the weak and wet strata, and that in strata which are firm, the concrete be allowed to flow against the compacted earth walls so as to afford a high frictional value and reduce cost through the elimination of unnecessary permanent forms in such strata.

In accordance with my invention, concrete piles are constructed by employing a driving shell and mandrel of the usual type, with the exception that my mandrel is tapered at the lower section and enclosed by a tapered steel boot which remains in the ground. The purpose of the tapered boot or lower section is to increase the driving speed, to force aside obstructions instead of driving them down, and to allow penetration into the final solid strata of earth in a firm but gentle manner. The tapered lower section also decreases the likelihood of damaging and causing drift to the adjacent completed piles, and it also tends to decrease heaving of the earth around adjacent piles. Grooves are pressed into the surface of the tapered boot to permit ready removal of the mandrel.

In accordance with my invention the driving shell is surrounded by a shell sleeve which permits withdrawal of the driving shell when only a portion of the concrete has been poured. As soon as the concrete has partially set, the shell sleeves may be withdrawn and used in the driving of other piles. The shell sleeve insures against the deformation of the pile commonly caused by heavy earth pressures and in the driving of contiguous piles. It allows speedier driving, as the driving shell can be removed immediately after the initial batch of concrete has been deposited in the shell. It permits the use of free flowing concrete instead of a dry mix, thereby doing away with time con-

suming compression of the concrete important in common uncased pile construction. Furthermore, the shell sleeve permits the construction of a finished pile top in the pouring process, eliminating the expense of dressing the tops by a sledge hammer and chisel after the concrete has set. The pile cut-off can be made at any required elevation, whether below or above the ground, at very little added expense, and in many cases piles can be driven before the excavation is made where the pile cut-off is many feet below the ground; whereas, at the present time, foundation pits and trenches must be dug all over the site and the earth taken from them leveled off so as to allow easy movement of the pile driver.

The shell sleeve constructed in accordance with my invention is locked to the driving shell at desired points so as to cause the shell sleeve to penetrate the earth in unison with the driving shell when and as desired. A metal collar with lugs on its inner surface is fastened around the driving shell just above the shell sleeve, the lugs engaging recesses in the driving shell. Lugs are provided on the exterior surface of the collar so as to provide a connection with the shell sleeve for a means of raising the shell sleeve when desired. The shell sleeve may be provided the full length of the driving shell or may start at any intermediate point in the length of the driving shell, and end at or above the earth level, as required by the particular soil condition. The shell sleeve may consist of a steel pipe segment with a large enough diameter for the driving shell to slide through it, and which are locked in place vertically. The shell sleeve may be of one unit length or of multiple units with interlocking parts. The joining of adjacent sections is such that it will keep them in true alignment for resisting lateral earth pressures.

In the driving operation the shell sleeve may be driven in unison with the driving shell or it may be driven in advance of the driving shell, or after the driving shell has been driven in place.

Owing to the provision of separate shell sleeve segments, the sleeve may be placed around the driving shell after the lower edge of the driving shell has entered the earth. Furthermore, such segments may be placed around the driving shell and removed therefrom at will. Also in shipping and storing such segments may be nested, reducing thus the cost of handling.

The purpose of the shell sleeve is to protect the wet concrete until it has attained a certain amount of set and hardness, and to resist the danger of

damage to the upper section of the pile during the driving of adjacent piles. Furthermore, it insures that the completed pile therein shall be true to its predetermined shape.

- 5 The shell sleeve inner surface may be lubricated so as to prevent the concrete from adhering thereto during its setting. It should be withdrawn very slowly by the aid of a screw jack or the like, to prevent excessive bond or friction between the earth and concrete and the shell sleeve, and also so slow that no damage can be caused to the setting of the concrete.
- 10

In the drawings, Fig. 1 is a side elevation partly in cross-section of a pile driving assembly;

- 15 Fig. 2 is a vertical cross-section of the assembly with the mandrel removed and the concrete poured in place;

Fig. 3 is a horizontal cross-section along lines 3—3 of Fig. 2;

- 20 Fig. 4 shows the completed concrete pile in place;

Fig. 5 is a perspective view of a shell sleeve section;

- 25 Fig. 6 is a side elevation of the interlocking parts of two shell sleeve sections;

Fig. 7 is an enlarged view of the top portion of Fig. 2;

Fig. 8 is a horizontal cross-section along lines 8—8 of Fig. 2;

- 30 Fig. 9 is a vertical cross-section of one use of my invention, illustrating the screw jack for removing the shell sleeve;

Fig. 10 is an enlarged view of a vertical cross-section of my improved pile driving assembly.

- 35 When it is desired to drive a concrete pile into the ground which, throughout a portion of the entire length of the pile, is such that the concrete pile should not be exposed thereto before the concrete is fairly well set, then the arrangement shown in Figs. 1 to 8 is used.

- 40 A cylindrical mandrel 1 having a tapered point 2 and a head 3, is surrounded by a driving shell 4. The tapered point of the mandrel is surrounded by a tapered boot shell 5 having a heavy steel toe 6 and a flanged rim 7 within which the end of the driving shell 4 is seated. Also seated within the flanged rim 7 and surrounding the driving shell 4 is a shell sleeve 8. The shell sleeve is in sections (in the present case three sections), joined to one another by bayonet locks 9. Each shell

- 45 sleeve section consists of two halves A and B which are placed around the driving shell 4 and which are held together by means of tongues and grooves 10, tapered so as to prevent the halves 50 from coming apart. Bale wires may be tied around each section to temporarily hold them in place.

- The lower ends of each section are narrowed, as indicated at 11, and on this portion is provided the lug 12 which cooperates with the bayonet joint lock of the succeeding section which slips over the narrow portion 11. The topmost section of the shell sleeve has a projecting rim 13 on which is seated a clamping ring 14. The clamping ring is of two sections pivoted at 15, and may be locked together at 16. Lugs 17 projecting from the ring 14 engage corresponding notches in the driving

shell 4. By means of hooks 18, the ring 14 is clamped to lugs 19 projecting from the flange 13.

When the whole assembly as above described is driven into the ground, the tapered boot shell 2 is subjected to great strain. In order to permit ready withdrawal of the tapered section 2 of the mandrel, the boot is protected by the heavy steel toe 6 and also by grooves 20 formed in the boot shell. Owing to the presence of these grooves the boot shell will be permitted sufficiently to spread so as not to bind the tapered end of the mandrel in place.

80 After the complete assembly is driven to the desired depth, the mandrel is withdrawn and concrete 21 is poured into the driving shell (Fig. 2).

90 The locking ring 14 is now removed, whereupon the driving shell may be immediately withdrawn without waiting for the setting of the concrete.

The concrete 21 is now permitted to set and harden, whereupon the shell sleeve 8, the inner

95 surface of which is lubricated so as to prevent cohesion between the setting concrete and this shell sleeve, is slowly withdrawn from the earth section by section. Any suitable lifting arrangement that will insure this may be utilized.

100 The one illustrated in Fig. 9 consists of a screw jack 22 cooperating with a head 23, which engages the flange 13. The screw jack bears against the top of the concrete pile.

If the lower strata of the ground are such that 105 other protection of the concrete is necessary, then before pouring the concrete an inner corrugated shell 24 is dropped within the driving shell 4 with a cone-shaped tapered end 25 projecting within the boot 5. The height of this 110 permanent inner shell is determined by soil conditions.

Owing to the provisions of the shell sleeve 8, the upper end of the concrete 21 can be finished off at any desired height below or above the ground, 115 as indicated in Fig. 3.

The concrete piles may have a circular cross-section or cross-sections in other shapes.

What is claimed is:

1. A form for concrete structures to be cast in 120 place comprising pairs of metallic sections, one pair being superimposed on another, means for attaching one section to its pair against longitudinal movement with respect thereto, and locking means between superimposed sections. 125

2. In the casting in place of concrete piles, a driving shell, a corrugated tapered boot having an enlarged rim in which said driving shell is seated, a shell sleeve surrounding said driving shell and composed of sections also seated in said 130 rim, each section consisting of two segments and having means of interlocking with an adjacent section, and means for lifting said shell sleeve.

3. In the casting in place of concrete piles, a driving shell, a shell sleeve surrounding said driving shell and composed of sections each section consisting of two segments and having means of interlocking with adjacent section, and means for withdrawing said shell sleeve independent of said 135 driving shell.

140 WILLIAM R. MARSDEN.
